CA 152610 8/2014

Primary Examiner — Melanie H Tung*Assistant Examiner* — Bao-Yen T Nguyen(74) *Attorney, Agent, or Firm* — Calfee, Halter & Griswold LLP(57) **CLAIM**

The ornamental design for a table top air purifier with a projector, as shown and described.

DESCRIPTION

FIG. 1 is a perspective view of a table top air purifier with a projector of a first embodiment of the new design;

FIG. 2 is a top plan view of the table top air purifier with a projector of FIG. 1;

FIG. 3 is a front elevational view of the table top air purifier with a projector of FIG. 1;

FIG. 4 is a left side elevational view of the table top air purifier with a projector of FIG. 1;

FIG. 5 is a right side elevational view of the table top air purifier with a projector of FIG. 1;

FIG. 6 is back elevational view of the table top air purifier with a projector of FIG. 1; and,

FIG. 7 is right bottom view of the table top air purifier with a projector of FIG. 1.

The broken lines illustrate portions of the air purifier and form no part of the claimed design.

The screen on the face of FIGS. 1 and 3 is shown in broken lines and forms no part of the claimed design.
